DESIGN FOR AN ANTITHEFT WHEEL ATTACHMENT OR SIMILAR ARTICLE

Harry O. Williams, Kansas City, Mo.

Application May 23, 1942, Serial No. 106,989

Term of patent 3½ years

To all whom it may concern:

Be it known that I, Harry O. Williams, a citizen of the United States, residing at Kansas City, in the county of Jackson and State of Missouri, have invented a new, original, and ornamental Design for an Antitheft Wheel Attachment or Similar Article, of which the following is a specification, reference being had to the accompanying drawing forming a part thereof.

Fig. 1 is a front elevational view of an antitheft wheel attachment or similar article, showing my new design.

Fig. 2 is a side elevational view thereof; and
Fig. 3 is an end view thereof.

I claim:

The ornamental design for an antitheft wheel attachment or similar article, as shown.

HARRY O. WILLIAMS.
